Primary Examiner — Karen E Kearney*Assistant Examiner* — Nathaniel D Buckner(74) *Attorney, Agent, or Firm* — Banner & Witcoff, Ltd.(57) **CLAIM**

The ornamental design for a biomedical signal recorder with a radio function, as shown and described.

DESCRIPTION

FIG. 1 is a front, bottom and right side perspective view of a biomedical signal recorder with a radio function, showing our new design;

FIG. 2 is a rear, top and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged sectional view thereof taken along the line 9-9 in FIG. 3; and,

FIG. 10 is an enlarged sectional view thereof taken along the line 10-10 in FIG. 8.

The broken lines in the figures represent portions of the article which form no part of the claim.
